UNITED STATES PATENT OFFICE.

JAMES CARLILE WHITEMAN, OF RICHMOND, ENGLAND.

CARBURETOR.

Application filed July 27, 1926, Serial No. 125,148, and in Great Britain October 13, 1925.

This invention relates to improvements in carburetors for use, for example, with internal combustion engines, and has for an object to provide an improved means for ensuring the satisfactory vaporization of heavy fuels, such as paraffin, alcohol, gas oil and even heavier hydro-carbons.

In accordance with the invention the atomizing chamber or the like of the carburetor is traversed by a tubular heating device, consisting of a plurality of tubes, or a coil, the tubes or the helices of the coil being arranged sufficiently close together, or being of sufficiently large diameter in relation to the dimensions of the atomizing chamber, to ensure that the fuel including any liquid particles passing between them will be completely vaporized, any liquid particles being either vaporized by radiation or by striking the heated tubes.

The tubular heating device may be heated by means of the exhaust gases or may be heated by hot water from the radiator and the degree of heat may be regulated by means of a valve or the like.

To obtain the greatest heat transfer a substantially constant speed of flow of the heating medium through the heating device is necessary. For this purpose, the heating device at the inlet end for the exhaust gases nearest the engine must be of greater cross sectional area than the outlet end to compensate for the contraction of the gases at the inlet end due to cooling by the mixture flowing to the engine. To obtain the required expansion of the mixture the surrounding atomizing chamber must be of gradually increasing free cross-sectional area from the carburetor end to the engine end of the space occupied by the heating device.

In one form the heating device consists of two or more tubes extending in the longitudinal direction of a pyramidal atomizing chamber and traversed by heating fluid such as the exhaust gases from the engine or hot water from the radiator of the engine, such tubes being connected at one end to a single inlet pipe and at the other to a single exit pipe. By distributing the gases supplied by the inlet pipe over two or more tubes extending in the longitudinal direction of a pyramidal atomizing chamber the flow of the hot exhaust gases or hot water through the pipes is retarded whereby to permit the maximum extraction of heat therefrom.

The invention thus provides a heating device of which the passages for the heating fluid converge towards the outlet end and of which the passages for the carbureted air diverge towards the outlet end.

The gradual reduction in cross sectional area of the heating device is designed to maintain the velocity and pressure of the hot exhaust gases passing therethrough. The maintenance of the velocity keeps the tubes of the heating device clear of deposited carbon, and the maintenance of the pressure ensures the best transfer of heat through the walls of the heating device.

One embodiment of the invention is illustrated diagrammatically in the accompanying drawing, in which Fig. 1 is an elevation partly in section of the improved heating device embodied in a carburetor; Fig. 2 a plan view partly in section of the atomizing chamber; Fig. 3 is a view of the heating device shown apart from its enclosing casing.

In accordance with the invention and as shown in the atomizing chamber A or the like of the carburetor, which chamber is suitably of pyramidal form, is disposed a tubular heating device indicated generally by B and comprising a plurality of tubes B' extending in the longitudinal direction of the chamber A, or of a coil through which is adapted to be passed heating fluid such as the exhaust gases of the engine or hot water from the radiator, in such manner that the fuel passing through the atomizing chamber A on its way to the induction pipe C is completely vaporized either by radiation from or by impact on the heated surfaces.

As shown and as preferred, the tubes B' are connected at one end with a single inlet pipe D connected with the exhaust pipe (not shown) and at their other ends to a single exit pipe E, which may also be connected to the exhaust pipe or may lead to the atmosphere. The ascending fuel strikes against the pipes E, B', B', flows around the spaces F between the heating device B and the atomizing chamber A and between the tubes B' to the induction pipe C leading to the inlet manifold of the engine. A baffle G is preferably interposed between the induction pipe C and the atomizing chamber A so as to prevent short circuiting of the particles of fuel and air and atomized fuel through the atomizing chamber A.

It will be seen that the passages for the

heating fluid converge towards the outlet end and the passages for the carbureted air diverge towards the outlet end:

It has been found that using petrol or alcohol as the fuel and using the tubular heating device described the fuel is converted into a warm gas, and that due to quick ignition rapid propagation of the explosion and perfect combustion are obtained in the engine cylinders resulting in a very low consumption of fuel, high power and rapid acceleration.

I claim—

1. In a carburetor for internal combustion engines in combination, an atomizing chamber for the fuel having walls diverging from the inlet to the outlet, and a tubular heating device comprising a plurality of passages disposed within said diverging walls and adapted to be traversed by a fluid heating medium, said passages converging in the direction of flow for the heating fluid.

2. In a carburetor for internal combustion engines in combination an atomizing chamber for the fuel having a portion of diverging form, and a tubular heating device disposed

in said diverging portion and adapted to be traversed by a fluid heating medium, said heating device having a single inlet and a single outlet and tubes disposed longitudinally between said inlet and said outlet and presenting, with said inlet and outlet, passages for the heating fluid decreasing in cross sectional area from inlet to outlet.

3. In a carburetor for internal combustion engines in combination, an atomizing chamber having a portion diverging from its inlet to its outlet, heating means disposed within the diverging portion of said atomizing chamber, said heating means including a plurality of tubes extending longitudinally of said atomizing chamber and presenting passages of cross sectional area decreasing with decreasing dimensions of the atomizing chamber, a single connection between said tubes at one end thereof, and a single connection between the tubes at the other end thereof, said connections leading to the exterior of the atomizing chamber.

In testimony whereof I have signed my name to this specification.

JAMES CARLILE WHITEMAN.
